The ornamental design for a modular caliper, as shown and described.

DESCRIPTION

FIG. 1 is a top planar view of a first embodiment of said modular caliper;

FIG. 2 is a rear elevational view of that which is shown in FIG. 1;

FIG. 3 is a front elevational view of that which is shown in FIG. 1;

FIG. 4 is a left side view of that which is shown in FIG. 1; FIG. 5 is a right side view of that which is shown in FIG. 1; FIG. 6 is a bottom plan view of that which is shown in FIG. 1;

FIG. 7 is a perspective view of that which is shown in FIG. 1 with gauge closed; and,

FIG. 8 is a perspective view of the embodiment shown in FIG. 1 with gauge opened.
